Patented Mar. 22, 1921.

UNITED STATES PATENT OFFICE.

WILLIAM T. S. WARNER, OF YUMA, ARIZONA.

COMBINED DRILL AND UNDERREAMER.

1,372,379.

Specification of Letters Patent. Patented Mar. 22, 1921.

Application filed June 1, 1920. Serial No. 385,569.

To all whom it may concern:

Be it known that I, WILLIAM T. S. WARNER, a citizen of the United States, residing at Yuma, in the county of Yuma and State of Arizona, have invented new and useful Improvements in Combined Drills and Underreamers, of which the following is a specification.

The present invention relates in general to 10 drills for drilling wells and the like, and has reference more particularly to a combined drill and under-reamer.

The primary object of the invention is to provide a structure of the class described 15 which will enable the well to be drilled and under-reamed to enlarge the hole for the well casing in one and the same operation.

An apparatus of this kind has many advantages, for instance, it will enable the 20 drilling apparatus to be operated through the well casing without reducing the diameter of the hole, thus enabling the operator to keep the casing following close behind the drill at all times, and in this manner exclude 25 surplus water from the hole and avoid the inconvenience arising when the hole caves in. Still another advantage consists in enabling the hole to be drilled at any depth with but one size of casing throughout from top 30 to bottom of the hole.

The accompanying drawing illustrates one manner of reducing the invention to practice. In said drawing, Figure 1 is a vertical section of a well, illustrating the 35 position the apparatus will assume in the hole when raised above the hole floor. Fig. 2 is a similar view showing the apparatus dropped. Fig. 3 is a vertical section of the top part of the apparatus. Fig. 4 is a sectional view on the line 4—4 Fig. 3. Fig. 5 is a side elevation of the lower part of the 40 apparatus and partly in section. Fig. 6 is a sectional view on the line 6—6 Fig. 5, and Fig. 7 is a vertical sectional view of the 45 lower part of the apparatus.

Referring now to the drawings in detail, for the purpose of convenience, the well will be hereinafter referred to as a hole and the hole may be drilled for any purpose, for 50 instance, as an oil well or for the purpose of reaching water under-ground. As is customary, particularly in drilling oil wells, sections of casing 1 are used as the drilling proceeds. According to the present inven-

tion the drilling apparatus will work within 55 the casing and of course extend below the end of the same to increase the depth of the hole. The drilling apparatus particularly the drill is never of the same diameter as that of the casing. Consequently, it does 60 not produce a hole with a diameter sufficient to accommodate the casing. As heretofore practised, the hole, after being made by the 65 drill, is usually reamed out to accommodate the casing. With the present apparatus the drilling and reaming out of the hole is done in the same operation and by means which are arranged in coöperative relationship to effect such a result in the most convenient 70 and satisfactory manner.

In reducing the invention to practice, it is proposed to employ a suitable drill, for instance, an ordinary so-called churn drill 2 will suffice providing it has a tapered top portion 3 adapted to have a threaded engagement 4 with the end of the drill rod 5 and with a set screw or the like 6 associated with this threaded connection for preventing turning of the drill relative to the 75 rod after it has once been screwed into position. This drill rod 5 extends upwardly and is inclosed by a suitable casing 7 which snugly fits the same, at the same time enabling the rod to reciprocate or slide therein, without undue amount of friction. A sleeve 8 having a threaded engagement on the end of the casing is provided with a pair of oppositely disposed ears 9 made to connect a pair of links 10 through the hinges 11. The lower ends of these links are connected 85 by means of a second set of hinges 12 with the under-reamer spades 13. These under-reamer spades are constructed with relatively sharp and outwardly flaring cutting edges 14 and they are further constructed 90 with a curvature which will enable them to conform to the contour of the tapering top part 3 of the bit 2. Arranged on the inside of each of the spades is a relatively narrow and elongated dovetail block 15 made as an 100 integral part of the spades and adapted to be confined in a dovetail groove 16 on opposite sides of the bit 2. These dovetail grooves 16 are arranged parallel to the sides of the tapering part 3 of the bit. Consequently, they converge in a direction toward the top of the bit. Thus when the spades are caused to be guided downwardly, they will 105

be spread out, so-to-speak, enabling their cutting edges 14 to act upon the hole and cut away the same to increase its diameter. As the spades are raised, or rather guided, 5 upwardly, relatively to the bit they will be brought inwardly which will enable them to pass the end of the casing 1 so that the bit may be raised a sufficient distance above the floor of the hole to effect the necessary 10 drilling action. As the spades 13 are primarily carried by the sleeve 8 and, as stated, as the sleeve has a threaded engagement with the end of the casing 7, the throw of the spades may be adjusted by turning the 15 sleeve 8 up or down. A locking device 17 is arranged to engage both the sleeve and the casing 7. This locking device comprises a metal strip having an inwardly presented spur 18 made to be received in an opening 20 in the casing 7 and with its lower end received within a vertical groove in the sleeve 8. A suitable bolt 19 is made to securely hold the locking device on the casing 7 to maintain the spur 18 in the opening in the 25 casing and the lower end of the device in the groove in the sleeve 8.

Arranged near the top of the rod 5 is a block 20 which is carried by a radial slot in the rod 5 and made to project beyond the 30 sides thereof and made to be confined in the slots 21, provided on opposite sides of the casing 7. The block working in these slots provides a stop for realizing the functioning of the device and inasmuch as the impact between the block and the respective ends of the slots will be considerable, it is proposed to add solidity to the structure by using a pair of attached plates surrounding the slots which plates may be riveted or otherwise 35 fixed to the casing. The block 20 is provided with a head 23 and a removable flange 24 which is confined on the opposite side of the block by means of bolts or the like. In this manner the flange 24 may be removed 40 and the block withdrawn through the radial slot to enable the rod 5 to be withdrawn from the casing 7. The head 23 and the removable flange 24 are adapted to overlie the plates 22 as their width is wider than that 45 of the slots 21. The end of the rod 5 will terminate short of the top of the casing 7 and is not in any way fixed to the casing other than through means of the block 20 so that same may be free to slide up and 50 down in the casing with such sliding movement restricted by the distance which the block 20 may move within the slots 21. The end of the casing 7 is threaded and made to receive a housing 25 of a swivel 26. A bolt 55 27 may be passed through the housing 25 and the casing 7 to effect a more or less permanently threaded engagement of these two parts. The swivel 26 is provided with an axial bore 28, the lower portion of which, 60 namely 29, gradually increases in diameter 65

so that the end of a cable may be received by the bore 28 and confined or rather wedged within the tapering portion 29. A suitable cap closure 30 is adapted to close the top of the device to exclude dirt, etc.

Attention is called to the fact that the drill 2 has a pair of oppositely disposed vertical grooves along its sides and also that the rod 5 has a pair of oppositely disposed vertical grooves extended substantially 75 throughout its length. The dove-tailed grooves 16 are open at their bottoms so that any dirt or other matter which may get into the same may be removed so as not to affect the proper functioning, or rather the 80 sliding movement of the spades 13.

I claim:

1. A drilling apparatus including a drill, a drill rod, a casing surrounding the drill rod, means connecting the casing with the 85 drill rod permitting a limited sliding movement of the rod therein, an under-reamer having an actuating connection with the casing and associated with the drill, and means for actuating the drill and under-reamer in 90 one and the same operation.

2. A drilling apparatus including a relatively long rod, a drill adapted to be carried on the end of said rod, a casing surrounding the rod and terminating above the drill, said 95 rod having a sliding movement in said casing and a stop for limiting said movement comprising an elongated slot in the casing and means carried by a rod and extending in said slot, an under-reamer comprising a 100 pair of spade-like blades having cutting edges and disposed on opposite sides of the drill, a link connection connecting the said blades with the casing, oppositely disposed guide-ways in the drill, means on the inner 105 side of said blades having a sliding movement in said guide-ways, and means for actuating the drill and the under-reamer in one and the same operation.

3. A drilling apparatus as set forth in 110 claim 2 in which the link connection connecting the under-reamer with the casing is capable of a vertical adjustment with means for maintaining the same.

4. A drilling apparatus embodying in its 115 construction a drill having a tapered upper portion, a drill rod to which the drill is mounted, a casing surrounding said rod, said rod having a sliding movement in the casing with a stop for limiting the same, an 120 under-reamer associated with the drill and actuated in one and the same operation as that of the drill and comprising a pair of spade-like blades arranged on opposite sides of the tapered upper part of the drill having 125 guides on their inner sides, guide ways extending vertically of the drill made to receive said guides, and a link connection connecting the under-reamer with the casing; whereby the sliding movement of the rod 130

within the casing will actuate to manipulate the under-reamer to throw the blades downwardly and outwardly of the drill in one direction and upwardly and inwardly of the drill in another direction.

5. A drilling apparatus as set forth in claim 4 in which the under-reamer blades are made with a curvature to conform to the

drill, and in which the blades are provided with outwardly flaring cutting edges.

6. A drilling apparatus, as set forth in claim 4 in which a swivel connection is arranged at the upper end of the casing adapted to receive a cable for actuating both the drill and the under-reamer.

WILLIAM T. S. WARNER.
